UNITED STATES PATENT OFFICE.

FREDERICK A. C. SKINNER, OF ST. LOUIS, MISSOURI.

PIPE-BENDING MACHINE.

Application filed April 25, 1924. Serial No. 708,946.

To all whom it may concern:

Be it known that I, FREDERICK A. C. SKINNER, a citizen of the United States, residing at St. Louis, in the State of Missouri, have invented certain new and useful Improvements in Pipe-Bending Machines, of which the following is a specification.

My invention has relation to improvements in pipe bending machines and consists 10 in the novel features of construction more fully set forth in the specification and pointed out in the claims.

The object of the present invention is primarily to bend a length of pipe into 15 coils of uniform length and having bends of a uniform radii, although it may be effectively used for bending rods or bars to any desired shape. A further object is to provide a power driven bending machine 20 which is automatic in its action except for feeding the machine which is manual. Further and other advantages will be better apparent from a detailed description of the invention in connection with the accompanying drawings, in which—

Figure 1 is a top plan of my improved bending machine; Fig. 2 is a front elevation thereof; Fig. 3 is an end elevation of the machine; Fig. 4 is an enlarged top plan 30 of the pipe bending mechanism at the end of the bending operation; Fig. 5 is an enlarged top plan of the bending mechanism in inoperative position, or idle, between bending operations; Fig. 6 is a combined 35 side elevation and middle vertical cross-section through the gear and bending mechanism mounted thereon; Fig. 7 is a cross-sectional detail taken on the line 7—7 of Fig. 4; Fig. 8 is a side elevation of the 40 pipe clamp hinged to the abutment member; Fig. 9 is a cross-sectional detail thereof taken on the line 9—9 of Fig. 8; and Fig. 10 is a sectional detail taken on the line 10—10 of Fig. 5.

Referring to the drawings, F represents a suitable structural supporting frame comprising posts 1, 1, etc., a marginal longitudinal member 2, and end members 3, 3 supported on said posts, and intermediate longitudinal members 4, 4 supported by the end members. Mounted on members 4, 4,

near each end is an upright spindle 5 having an annular shoulder 6, and a gear 7 is rotatably mounted on said spindle and rests on the shoulder 6. The bending mechanism 55 operated by gear 7 is the same at both ends of the frame F, hence only one unit will be described, it being understood that the present machine is made double, i. e., comprises two bending units, merely to increase 60 its efficiency. A pinion 8 is mounted on a shaft 9 having bearing at each end in suitable bearings 10, 10 secured to posts 1, 1, and said pinion meshes with a bevel gear 11, keyed to a vertically disposed shaft 12 65 mounted in a bearing 13 secured to one of the members 2. Shaft 12 carries a pinion 14 on its upper end said pinion meshing with and driving the spur gear 7. Shaft 9 is driven by a motor M having a drive 70 sprocket 15 connected to a driven sprocket 16 on shaft 9 by a chain 17. It is thus seen that gear 7, which is the proximate driving element of the bending mechanism is constantly rotating while motor M is running. 75 The bending mechanism with gear 7 as its foundation may now be described.

The spindle 5 over which gear 7 rotates, terminates at its upper end in a reduced portion 18 over which is placed an abutment member 19 held thereon by a nut 20 screwed over threads 21 on the end of said reduced portion, the abutment 19 being held against turning by being bolted to an angle 22 secured to frame members 4, 4. The 80 abutment member is provided with a circular side 23 and oppositely disposed straight sides 24 and 25 tangential to said circular side, and a continuous groove 26 is formed in said sides to receive the pipe 90 P to be bent as will more fully appear hereinafter. The circular part of groove 26 is concentric with the rotation axis of gear 7. Hingedly secured to the abutment member 19 is a clamp 27 for securely holding 95 the pipe in that part of groove 26 formed in the straight side 24 of the abutment, said clamp being described in detail below. The upper surface of gear 7 is provided with two annular shoulders α and α' , and the 100 face 28 of the gear bounded by shoulder α' is machined smooth and has a radial slot

29 formed in it, said slot opening into shoulder a , and being of slightly less depth than the combined height of shoulders a , a' . A driving dog 30 is slidingly fitted into slot 29, and has a recess 31 formed in its upper surface adjacent one side, and a stop screw 31' is screwed into the face 28 of the gear 7 on the edge of slot 29 so that the end of said screw will enter the recess 31 to limit the movement of the dog 30 in said slot. The dog 30 is shouldered at k near its free end and the nose 30 of said dog is urged out through the open end of the slot by a spring 32 positioned between the inner 15 end of said dog and closed end of the slot 29. A member 33 having a hub 34 at one end is slidingly mounted on the face 28 of gear 7, said hub being rotatably positioned over spindle 5 between gear 7 and abutment 20 19, and a pair of guides 35, 35, having their inner edges, e , e , inclined outwardly, are secured to the upper face of member 33 adjacent to the sides thereof. A slide plate 36 is adapted to slide over the member 33 25 as a base, confined by the guides 35, 35, said plate 36 having its edges e' , e' inclined to cooperate with edges e , e of the guides. The inner end of the slide plate 36 has a spindle 37 projecting upwardly from it on 30 which is mounted a grooved roller 38, said roller being held on the spindle by a nut 39 screwed over the threaded terminal 40 of said spindle, and the outer end of said plate 36 has one corner cut out at right angles 35 denoted by x , the margins of said cut away portion intersecting the boundary of a slightly more than semicircular recess y . The purpose of this formation will presently appear. The outer end of base plate 33 40 is provided with an opening 41 through which is passed a spindle 42 projecting from near one end of a lever 43, and a cam 44 is pinned to said spindle between base 33 and the marginal face of gear 7. The relation 45 of the parts is such that this places the cam 44 in close proximity to the nose 30' of dog 30 so that when the dog is expelled by spring 32 it will be in position to engage the cam 44 provided the high side of said cam is toward the dog. The function of 50 the cam will be better apparent from what follows. The short arm of lever 43 operated toward the center of gear 7 and its extremity is shouldered as shown (Fig. 6) 55 to receive the reduced end of a link 46, the opposite end 47 of said link being circular in shape and adapted to fit into recess y in plate 36. It should now be apparent that with an angular movement of lever 43 the 60 link 46 will be drawn out or forced in, depending on whether the lever is moved from or toward dead center with reference to its spindle 42, and the slide 36 will likewise be moved either out or in, and, further,

cam 44 will be rotated. It will now be apparent from Fig. 5 that the cut out corner x permits clearance for the swinging of link 46 when the lever 43 is oscillated to its angular position for withdrawing the roller 38 from abutment member 19. 70

It will be observed from Figs. 5, 6 and 7 that a lug n projects downwardly from the bottom of base plate 33 at a point slightly inside of and beyond the pivotal point of link 46 with respect to the direction of rotation of gear 7, and this lug n is directly in the path of travel of dog 30 when said dog is in its outermost position in slot 29. However, should cam 44 be turned to the position shown in Fig. 5 the nose 30' of said dog will impinge on said cam which forces the dog back in its slot so that the shoulder k will come inside the lug n and the dog will now pass under said lug. 80

The cam 44 is cylindrical except for slightly less than 90° of its peripheral surface. Extending from the base of cam face 45 is a cylindrical portion 44' of reduced radius, and an inclined face 45' connects the portion 44' with the outer cylindrical 90 surface 48. 85

In order to secure the pipe P to the member 19, the clamp 27 is provided, said clamp comprising a block 50 hinged at 49 to clamp 19, and a clamp member 51 pivotally connected at 52 to one end of said block. A pin 53 is rotatably mounted in the block near the other end, said pin carrying a lever 54 at one end and an eccentric 55 at the other end, said eccentric being rotatable in a slot 56 in the clamp member. After the pipe has been placed in groove 26 of the abutment member, the block 50 is swung downwardly (dotted Fig. 9) so that toothed groove 57 in the member 51 embraces the pipe after which the lever 54 is pulled down to cause the clamp member to come tightly into engagement with said pipe. 100 105

A trip 58 is provided for tripping the lever 43 at the end of a bending operation and a spring latch 59 is provided for holding said lever and associated parts in inoperative position between bending operations. 110

In order that the pipe P may be supported during the bending operation a table T is provided between the gears 7 and extending to one side of them, said table being in the same plane with the bottom of abutment 19. In order that the point at which the pipe is to be bent can be quickly determined a series of holes 60 are placed in the table T and a gauge pin 61 inserted in that one which is spaced correctly from the abutment member to give the proper length coil when the pipe is bent. This will be better apparent from an inspection of Fig. 1. 115 120 125

In the operation of the machine, the

power of motor M is transmitted, through the gearing heretofore described, to each of the gears 7 so that they will be continuously rotating in opposite directions while the machine is in use. An operator is positioned alongside each gear 7 to perform such functions as are manual. We will assume that the bending mechanism comprising slide 36, roller 38 and associated parts are 10 in the position shown on the right hand side Fig. 1, which is the starting position for the bending operation. It will be noted (Fig. 5) that the lever 43 is in a position substantially at right angles to slide 36, side 15 slide and roller 38 having been withdrawn by the link connection 46 with said lever, away from the abutment member 19. For this position of the lever 43 the cam 44 is turned as shown in Fig. 5 and its radial 20 face 45 is out of the path of driving dog 30 the nose 30' of which is cammed by the outer periphery of cam 44 so that the dog 30 slips past the lug n. Thus the gear 7 may rotate idly when the lever 43 is in the 25 position just pointed out.

The operator now positions the pipe P that is to be bent, in groove 26 of the abutment member 19, and secures it therein by the clamp 27. The bending mechanism is 30 now brought into play by manually swinging lever 43 to its position shown in Fig. 9, almost in line with slide 36. This movement of the lever straightens the toggle comprised of said lever and link 46 which 35 forces the slide 36 and roller 38 inwardly toward abutment member 19, the groove of said roller embracing the pipe P. At the same time the cam 45 is rotated so that its face 44' comes opposite to the revolving 40 driving dog 30 which impinges on the lug n and against cam face 45 thus driving plate 33, with the parts mounted on it, around in front of it, and rotating the entire bending mechanism. At the same time the pressure 45 of the dog 30 against cam face 45 locks the toggle comprised of lever 43 and link 46. The rotation of roller 38 around abutment 19 obviously bends the pipe between the roller and abutment. When the pipe has 50 been bent to a semicircle the lever 43 is tripped by the trip arm 58, secured to the side of the table opposite to that on which the bending operation began, said lever being swung to the position shown dotted in 55 Fig. 4 and the toggle broken, thus withdrawing slide 36 and roller 38 and rotating the cam 44 so that cam face 45' forces the dog 30 back in its slot and releases the lug n so that rotation of the bending mechanism 60 is arrested. The gear 7, of course, with its driving dog 30 now rotates idly. The bending mechanism is now manually rotated back to the starting position shown in Fig. 5 and the lever 43 slipped behind the spring

latch 59. The bending operation may now 65 be repeated.

Having described my invention, I claim:

1. A pipe bending machine comprising a suitable frame, a disk rotatably mounted on said frame, a fixed abutment member centered over the rotation axis of said disk, a bending element rotatable about the axis of the disk and movable radially with respect to said axis, means for coupling the bending element to the disk and simultaneously moving same toward the rotation axis of said disk, and means for uncoupling said bending element and disk and simultaneously withdrawing the bending element. 75

2. A pipe bending machine comprising a frame, a disk rotatably mounted thereon, a fixed abutment member centered over the rotation axis of said disk, a bending element loosely mounted on said disk and movable radially with respect to the axis thereof, a driving dog carried by said disk, a lug on the bending element adapted to be engaged by said dog for rotating the bending element, and means for releasing said dog from the lug and simultaneously therewith moving the bending element outwardly from the rotation axis of the disk. 85

3. A pipe bending machine comprising a frame, a disk rotatably mounted thereon, means for rotating said disk, a fixed abutment centered over the rotation axis of said disk, a plate loosely mounted over said disk, a bending element mounted on said plate and slidable radially with respect to the rotation axis of the disk, a driving dog carried by said disk, a lug on the plate adapted to be engaged by said dog for rotating said plate, and means for releasing said dog from the lug and simultaneously therewith sliding the bending element outwardly on 90 100 the aforesaid plate. 105

4. A pipe bending machine comprising a frame, a disk rotatably mounted thereon, means for rotating said disk, a fixed abutment centered over the rotation axis of said disk, a plate loosely mounted over said disk, a bending element mounted on said plate and slidable radially with respect to the rotation axis of the disk, a lever mounted on said plate and having a toggle connection 110 with said bending element, a cam connected to said lever at the pivotal point thereof, a driving dog slidably mounted on said disk, a lug on said plate adapted to be engaged by the dog for rotating said plate and bending element, said cam being adapted to engage the dog to release same from said lug on swinging the aforesaid lever to a position for withdrawing the bending element from the rotation axis of the aforesaid disk. 115

5. A pipe bending machine comprising a frame, a disk rotatably mounted thereon, means for rotating said disk, a fixed abut-

ment centered over the rotation axis of said disk, a plate loosely mounted over said disk, a bending element mounted on said plate and slidable radially with respect to the rotation axis of the disk, a driving dog carried by said disk, a lug on the plate adapted to be engaged by said dog for rotating said plate, means for withdrawing the

bending element from the abutment member, and a cam for releasing said dog simultaneously with a withdrawal of the bending element.

In testimony whereof I hereunto affix my signature.

FREDERICK A. C. SKINNER.
